FREIGHT CONTAINER

Benjamin F. Fitch, Zaccheus Meade Lane, Fairfield County, Conn., and Ragnar A. Norbom, Nutley, N.J., assignors to Motor Terminals, Inc., Cleveland, Ohio, a corporation of Ohio

Application October 13, 1939, Serial No. 299,326

12 Claims. (Cl. 294—67)

A system of handling package freight by means of demountable bodies which may be carried interchangeably on highway trucks, railway cars or vehicles, and lifted with their contained loads from one such vehicle to another for transportation, has many advantages in expediting the speed of transportation and reducing the cost of shipping from consignor to consignee, and reducing the loss due to pilferage or breakage.

5 In a system of this character it is desirable that the lifting mechanism which raises and transfers the body be readily engaged with the body at four points corresponding to the four corners of a horizontal rectangle. Lift hooks attached to the body adjacent the eaves, two on one side and two on the other, have been found to provide for the ready engagement of the hoisting mechanism. Such hooks, however, may become bent or damaged in use, and it is desirable to provide 10 means for the ready replacement of the hooks themselves, wherever the body is located, without requiring skilled labor, or the sending of the body to a repair shop.

Our invention accomplishes the above object by providing on the body itself adjacent the eaves a very efficient, permanently attached anchorage for the hook, and forming the hook in such manner that it may be effectively engaged with such anchorage and held thereto in use, but may be 15 readily removed therefrom whenever desired.

Our invention comprises the means by which we accomplish the above result, as illustrated in the drawing hereof, and hereinafter more fully described and set out in its essential characteristics in the claims.

In the drawing, Fig. 1 is a side elevation of a demountable body, provided with our removable lift hook, and permanent anchorage therefor, this view showing also a suitable hoist cradle engaged with the hooks; Fig. 2 is a fragmentary side elevation on a larger scale of the hook and anchorage and the intermediate adjacent portion of the body; Fig. 3 is a vertical cross-section through part of the anchorage and part of the 20 shank of the hook in a plane indicated by the line 3—3 on Fig. 2; Fig. 4 is a perspective of the hook shank; Fig. 5 is a perspective of the socket constituting the anchorage for the hook; Fig. 6 is a horizontal cross-section through the upper 25 portion of the socket as indicated by the line 6—6 on Fig. 5.

Figs. 1, 2 and 3 indicate at 10 the side wall of a demountable body, it being understood that this body may be rectangular in plan having a 30 suitable floor (not shown), parallel sides 10, par-

allel ends 11, and a roof 12. The side wall as shown is provided with a pair of panelled doors 15, hingedly mounted.

The body sides are provided with braces between the door frame and the ends of the body. 5 As shown, these braces comprise a vertical strip 16 directly in line with the application of the lifting force, and diagonal brace bars 17 extending downwardly from a point near the top of the strips 16 to regions comparatively near the ends 10 of the body and comparatively near the end of the door frame, respectively.

The side walls 10 are preferably of sheet steel, and the vertical strip and brace bars are welded to such steel plate. The intermediate brace 16 15 is preferably a flat strap extending from the eave to the base of the car. The braces 17 are preferably angle bars, one flange of which is welded to the side sheet of the body, with the other flange projecting at right angles to the 20 body, these angle bars being rights and lefts so that the projecting flanges are adjacent each other.

Between the two adjacent flanges 18, near their upper ends, I mount the socket 20 for the lift 25 hook. This socket is a metal casting or forging of the general form indicated in Fig. 5; it receives and holds the lift hook 30 by reason of peculiar interengaging shoulders on the seat and hook, which will now be described.

The socket 20 which is of such material that it may be welded to the body side and braces, is an open box-like member in the form shown in Fig. 5. As there shown, it comprises the following parts, all integral with each other, name- 35 ly; a plate-like body portion 21, which intermediately is offset backwardly to provide the back plate 22, and the connecting webs 23. The channel between the webs 23 is closed by a web 24 at the top, and by a hollow projecting boss 25 40 at the bottom. At opposite sides of the boss are a pair of projecting wings 26 which lead from the edges of the plate-like portion 21. Each wing is thickened gradually, as one measures downwardly, as shown at 27, and terminates in 45 an abrupt horizontal shoulder 28 at the bottom. Each shoulder is intermediately interrupted by an upwardly extending notch 29 formed therein.

The hook 30 is nearly flat, except that it converges toward the edge opposite its opening, as 50 shown at 31, in Fig. 3. The hook has a flat shank 32, at the lower portion of which are laterally projecting ledges 33, the upper faces of which are horizontal. On the upper face of these ledges, formed integrally with them and with 55

the shank, are parallel-sided bosses 34. Near its bottom the shank 32 is recessed on opposite sides, by approximately semi-circular recesses 35. Between these recesses in the central plane of the hook is a thinner, downwardly extending eye portion 36. The opening 37 of this eye is in line with the center of the shank, and with the highest point of the hook opening.

The dimensions of the socket and shank above described are such that the shank may stand between and substantially in engagement with the inner vertical face of the widest portion of the socket wings. In active position, the ledges 33 of the shank will stand beneath and engage the under-face of the shoulders 28 of the socket, and the bosses 34 rising from the ledges will occupy the notches 29, and the opening 37 will register with the opening of the boss 25 of the socket.

The socket member above described is permanently attached to the side of the body of container. The flare of the two side wings 26 on their exterior is at the same angle as the flare of the projecting flanges 18 of the diagonal braces 17 on the body side. The socket is put in place between these diagonal braces and shoved upwardly in tight contact with the flanges thereof, and is welded to such flanges while the back plate 22 of the socket member is welded to the bracing strap 16 of the side. This socket thus becomes permanently attached, and effectively held to the body side.

The recess 35 in the shank has sufficient clearance over the boss 25 that the hook may be shoved laterally into place between the wings of the socket with the bosses 34 on the hook just below the bottom plane of the shoulders 28; then, when the bosses 34 come into alignment with the notches 29, the hook may be lifted to carry those bosses into the notches. This brings the opening 37 of the hook shank into registration with the central bore of the boss 25. Such bore is intermediately threaded, as shown at 41. When the hook is in place, a cap screw 40 is passed through the eye and screwed into the thread 41 of the boss 25. A suitable lock washer 42 prevents inadvertent working out of the cap screw.

It will be seen that the vertical stresses as the body is being lifted or supported are taken directly from the hook shank and its ledges to the socket member, thence to the body side and braces. The engagement of the vertical inner faces of the thickened socket wings with the vertical edges of the hook shank prevent shifting or tipping in a longitudinal direction of the hook; while lateral stresses on the hook are taken care of by the engagement of the inner face of its shank with the strap 16, and by the engagement of the bosses 34 with the walls of the socket notches. Accordingly, all of such stresses are resisted independently of the bolt or cap screw 40, which need merely serve to hold the hook in place when it is idle.

The mounting of the hook socket between the converging brace bars 17 and the welding of the socket to the bars and to the body side makes a very effective, permanent attachment of the socket to the side, so that lifting stresses are readily distributed from the hook to the socket and along the brace bars to the floor frame of the body.

It will be noticed that recesses 35 in the shank adjacent the eye are made on both sides of the hook, with the result that the hook is reversible, and may be mounted in the socket with either face of the shank inwardly; that is to say with the

hook faced toward either end of the body, as desired.

With our invention, in the case of a damaged hook, it is a very simple matter for a workman at any location, and by the mere use of a suitable wrench, to unscrew the bolt 40, remove the hook and replace it by a new hook, and restore the bolt.

We claim:

1. A demountable truck body provided with a permanently secured anchorage, a detachable hook having a shank formed with a projection to underhang a portion of said anchorage, and means for holding the shank in coaction with the anchorage, whereby lifting stresses on the hook are automatically passed to the anchorage and then to the body.

2. A demountable container provided with a permanently secured socket with an open side, a hook having a shank adapted to be passed laterally into the socket and formed to underhang a portion thereof, and means for holding the shank in place in the socket.

3. The combination of a container having converging braces on its side, a hook anchorage secured to the container side and arranged to engage the adjacent faces of the braces, and a hook adapted for removable attachment to the anchorage.

4. The combination of a container, a hook secured to the container and having a back with projecting wings and an open front and a hook having a shank adapted to stand between the wings and having projecting ledges adapted to underhang portions of the wings.

5. The combination of a container having a vertical side, a pair of converging braces secured to the side adjacent each other near the top, a hook socket having flaring opposite edge faces, said edge faces engaging the braces and secured thereto, the socket providing downwardly facing shoulders, and a hook having a downwardly extending shank adapted to occupy the socket and formed with projecting ledges at its opposite edges, the ledges being adapted to stand beneath said shoulders.

6. The combination of a container having a vertical side, a hook socket secured to said side and having spacially arranged projecting wings which provide downwardly facing shoulders, a hook having a downwardly extending shank substantially filling the space between the wings, said shank having projecting ledges at its opposite edges, the ledges being adapted to stand beneath said shoulders, and means for holding the shank fixedly within the socket.

7. The combination of a container having a vertical side, a pair of converging braces secured to the side adjacent each other near the top, a hook socket having a flat back and flaring opposite edge faces, said back being welded to the container side and said edge faces welded to the braces, a hook having a downwardly extending shank adapted to occupy the socket with a projection on the shank underhanging a shoulder on the socket, and means for holding the shank fixedly within the socket.

8. The combination of a container, a hook socket secured thereto and having spaced wings providing downwardly facing shoulders, a hook having a downwardly extending shank with projecting ledges at its opposite edges, the ledges being adapted to stand beneath the shoulders on the socket, and coacting bosses and notches associated with the shoulders and ledges, to re-

strict movement of the shank away from the body side.

9. The combination of a container, a hook socket secured to the wall thereof, and having a 5 pair of spaced outwardly projecting wings, said wings having shoulders on their undersides provided with notches, and a hook having a shank adapted to stand between the wings, the shank having oppositely projecting ledges adapted to 10 lie beneath the shoulders of the socket, and the ledges having upwardly extending bosses adapted to occupy the notches.

10. The combination of a container, a hook socket secured to the wall thereof, and having a 15 pair of spaced outwardly projecting wings, said wings having downwardly facing shoulders, a hook having a shank adapted to stand between the wings, the shank having oppositely projecting ledges adapted to lie beneath the shoulders of the socket, the socket being formed with 20 an outwardly projecting hollow boss and the shank having an eye the opening of which is adapted to register with the opening of the boss when the shank is in place, and a bolt occupying the openings of the eye and boss to prevent separation of the parts.

11. The combination of a container, a socket member secured thereto and having outwardly projecting wings, each with a thickened portion 30 on its inner side providing an abrupt downwardly facing shoulder, and a hook having a shank substantially rectangular in cross-section the shank lying between the thickened portion of the wings, the shank having ledges at its opposite edges 35 adapted to project beneath the thickened portion of the wings and engaging the same, there being

bosses and notches on the wings and ledges to prevent movement of the shank away from the body side when the bosses are in the notches, the socket and shank being provided with a hollow boss and an eye which registers with the 5 boss when the shank is in place, and a bolt occupying the eye and boss to lock the positioning hook in the socket.

12. The combination of a container having a vertical side, a pair of diagonally positioned angle 10 bars welded to the side, said bars converging upwardly and being comparatively close to each other adjacent the eaves of a container, a metal socket member between the bars and welded to the container side and having outwardly projecting diagonally faced wings welded to the adjacent flanges of the angle bars, each wing having a thickened portion on its inner side providing an abrupt downwardly facing shoulder, and a hook having a shank substantially rectangular in 20 cross-section the shank lying between the thickened portion of the wings, the shank having ledges at its opposite edges adapted to project beneath the thickened portion of the shanks and engaging the same, there being upwardly extending bosses on the ledges and coacting notches in said thickened portions to prevent movement of the shank away from the body side when the bosses are in the notches, the socket being provided with a hollow boss and the shank with 30 an eye which registers with the boss when the shank is in place, and a bolt occupying the eye and boss to lock the positioning hook in the socket.
